(57) **CLAIM**

The ornamental design for a support for an electronic camera, as shown and described.

DESCRIPTION

FIG. 1 is a front perspective view of a support for an electronic camera showing my new design;

FIG. 2 is a front view thereof;

FIG. 3 is a rear view thereof;

FIG. 4 is a side view thereof;

FIG. 5 is a second side view thereof;

FIG. 6 is a top view thereof;

FIG. 7 is a bottom view thereof;

FIG. 8 is a front perspective view of the support for an electronic camera of FIGS. 1-7 shown in isolation;

FIG. 9 is a front view thereof;

FIG. 10 is a rear view thereof;

FIG. 11 is a side view thereof;

FIG. 12 is a second side view thereof;

FIG. 13 is a top view thereof; and,

FIG. 14 is a bottom view thereof.

The broken lines showing the electronic camera in FIGS. 1-7 are for environmental purposes only and form no part of the claimed design.
